4 Claims. (Cl. 80—23)

1

The present invention relates to the art of metal working, and, more particularly, to a machine for the roll-die formation of shapes from cylindrical billets, such as "dumbbell" contoured shapes as commonly used in the manufacture of turbine blades and other products.

Heretofore, in the production of turbine blades it has been the common practice, as an initial or intermediate step in the process, to convert billets of cylindrical form into "dumbbell" shapes by expensive swaging operations. Each of the dumbbell blanks so provided is employed for the production of one or two turbine blades by subsequent operations such as by die-pressing.

Although attempts have been made to facilitate the production of "dumbbell" or other deformed shapes from billets and to simplify the operational procedure as heretofore required, none of the prior attempts, as far as I am aware, was entirely successful when carried into practice commercially on an industrial scale.

It has now been discovered that the production of "dumbbell" and like intermediate or deformed shapes from cylindrical billets may with greater facility and with economic advantage be accomplished by the employment of an improved machine operating with the instrumentality of multiple roll-dies to effect the required deformation of the billet. The improved machine is of special design and structural arrangement providing for increased facility in the feeding or inserting of the billets to the machine with resulting operating economy and, further, incident to the roll-die deforming of the billet, produces a product of an improved roll-finished surface.

It is an object of the present invention to produce an improved machine for the roll-die deformation of cylindrical billets of special structural design and arrangement adapted to materially facilitate the deforming operation.

Another object of the invention is to produce a multiple roll-die deforming machine for billets having structural provision for introduction of the billets into working or deforming position in the direction axially of the roll-dies.

The invention also contemplates providing a multiple roll-die deforming mechanism for billets having an improved structural arrangement providing for introduction of the billets into position to be acted on by the roll-dies in a direc-

2

tion axially of the roll-dies and having associated therewith a yieldable stop member adapted initially to position the billet and to be yieldably deflected during the deforming of the billet to the finished shape.

Other objects and advantages of the present invention will become apparent from the following description taken in conjunction with the accompanying drawings, in which

10 Fig. 1 is a central vertical longitudinal sectional view of a machine embodying the features of the present invention and adapted for the roll-die formation of shapes from cylindrical billets and showing the roll-dies in position at the completion of the rolling operation;

Fig. 2 is an enlarged fragmentary view similar to Fig. 1 and illustrates the rolls in the starting position as the billet is received within the machine;

15 Fig. 3 is a cross-sectional view taken on line 3—3 of Fig. 1 and illustrates the means for driving the roll-dies;

Fig. 4 is a vertical cross section taken on line 4—4 of Fig. 1 and shows the roll-dies in position for the introduction of the billet;

Fig. 5 is a perspective view of the roll-dies; and Figs. 6 to 15 are pairs of diagrammatic longitudinal and cross-sectional views showing on a larger scale successive stages of the reduction of a billet.

Generally speaking, the present invention contemplates providing a multiple roll-die mechanism for the deforming of cylindrical billets having a special structural arrangement permitting introduction of the billets into position to be acted upon in a direction axially of the roll-dies, the provision of a special form of roll-die operating initially to deform the billet to the desired shape, and finally to roll-finish the product and further to have incorporated therewith a yieldable stop member operating initially to position the billet and to permit of the stop being yieldably deflected during the operation of deforming of the billet to the finished shape.

45 In the preferred embodiment of the invention as here illustrated, the improved machine comprises three rollers or roll-dies 2, 4 and 6, mounted on driven shafts 8, 10 and 12, journalled in a housing for the roll stand which is built up of four plates 15, 17, 19 and 21. Each of the shafts

8, 10 and 12 has affixed thereon a pinion 16 meshing with internal teeth on a gear ring 18. The gear ring 18 is likewise provided with external teeth 14 positioned in mesh with the teeth of a driving rack bar 20 slidably fitted to reciprocate in horizontal guide-way grooves 22 and 24 and operable with a stroke sufficient to turn the rollers 2, 4 and 6 through one revolution. The driving rack bar 20, as will be understood, may be operated by any suitable means to effect its reciprocation such as by a pneumatic plunger driving means, not shown. The three roll-dies 2, 4 and 6, as employed in the machine of the present invention, are identical and, as best shown in Fig. 5, are formed or shaped as a cylinder 26 with a ridge or forming cam shoulder 28 which extends circumferentially and increases in radius and width around the cylinder or roll. The roll-dies are arranged in such relative angular positions that corresponding parts of the roll-dies will simultaneously engage a billet inserted centrally through a hole 30 in the front or forward supporting plate 15. In the arrangement the three roll-dies are shown as equally spaced circumferentially thereby forming a cage for the reception of the heated billet indicated at 34. Clearance for the reception of the billet is provided by the cut-away or low portions of the metal working shoulders or cams. The roll-dies, as best shown in Fig. 5, are cut away at 42 at their outermost sides, thus providing reentrant portions providing clearance for the tongs by which the billet is placed in position to be operated on. The structural provisions for the driving of the rolls likewise provide for central longitudinal clearance through the machine.

In accordance with the invention and contributing to the improved manner of operation there is provided a yieldable stop which is adapted to be engaged by the billet for its proper initial positioning with relation to the roll-dies and which will be yieldable during the deforming operation to accommodate the deforming of the billet. The structural arrangement of the yieldable stop consists of a stop member 32 fitted to a socket in the forward end of a shaft or plunger 33 located within forward and rearward slide bearings 35 and 36 which are supported by a frame bracket 37. Plunger shaft 33 is normally urged forwardly by means of the coil spring 39 surrounding the shaft and interposed between the bearing 36 and a ring or bushing 40 on the shaft 33, which ring or bushing 40 engages a rearwardly directed shoulder on the forward or socket end of the shaft (Fig. 1). The rearward end of the plunger shaft 33 is provided with a threaded extension for the reception of adjustable nuts 38 which act as a stop to determine the initial or forward position of the stop member 32, as will be readily appreciated.

The operation on the billet starts with the rack bar 20 at the right-hand end of its stroke and the roll-dies in the position shown in Figs. 2 and 4. The billet is initially heated until it will flow under pressure and it is then fed into the machine between the roll-dies until it engages the stop 32. The rack bar 20 is then moved by its power source to the left to its position as seen in Fig. 3. The rollers 2, 4 and 6 are in consequence turned clockwise while the billet is rolled anti-clockwise between them. The progressive effect of the engagement of the forming ridges or cam shoulders 28 with the billet 34 is indicated in Figs. 6 to 15 as producing a shape of dumbbell formation.

The formation of the roll-dies is such that during the latter part of the operation, the ridge engaging the billet is of constant radius and as a result advantageously smooths the surface of the reduced part of the billet. During the formation of the billet, the stop 32 yields a short distance to allow for the extension of the reduced part of the billet. During the die formation of the shape, the end portions 44 and 45 increase slightly in diameter and are shaped by the cylindrical surface 26 of the roll-dies. After the rolls have completed a revolution the billet is withdrawn, the forming shoulders 28 being by then clear of the inner head of the shape and the cylindrical part of the rollers being slightly cut away at 48 to permit the billet to be withdrawn freely. Withdrawal is assisted by the spring 39. For subsequent operation, the rack bar 20 is then returned to its initial position.

After the billet has been withdrawn, it may be severed to provide a mushroom-shape piece of metal which is hot pressed to the final shape of a turbine blade. If it is desirable to have the reduced part of the billet of tapered shape, the ridges may have slightly coned outer surfaces as will be readily understood. While the mushroom-shape may be produced by simply cutting in half a dumbbell of appropriate length it may likewise be produced by placing a suitable billet in the machine in such a way that it is left with one head only.

It is to be observed that the machine embodying the present invention is designed with roll-dies for deforming of billets in such a manner as to permit the insertion or introduction of the billets into the machine in a direction axially of the roll-dies. Furthermore, the machine has incorporated therein a yieldable stop member which materially contributes to the successful operation of the machine in the manner described herein.

Moreover, the roll-dies employed have an effective and improved formation capable of operating progressively to deform the billet to the desired shape, capable of permitting the introduction and withdrawal of the billet or shape axially of the rolls in the finishing of the shape, and also capable of operating on the work in a manner providing an advantageous rolled surface finish.

In the multiple roll-die machine embodying the features of the present invention, three roll-dies are preferably employed and are equally spaced around a central cage space. The cam surface or forming shoulder proper extends through about 270° on each of the roll-dies and thereafter merges with a plane cylindrical surface so that during the last part of the rotation of about 90°, the shape is rolled between three such cylindrical surfaces so as to give a good surface finish. The axial edges of the forming cams or shoulders may, as shown, be sloped off so as to exert a wedging action on the billet and so as to assist the axial extension which accompanies the reduction in diameter.

Although the present invention has been described in conjunction with preferred embodiments, it is to be understood that modifications and variations may be resorted to without departing from the spirit and scope of the invention, as those skilled in the art will readily understand. Such modifications and variations are considered to be within the purview and scope of the invention and appended claims.

I claim:

1. A machine adapted for forming a "dumb-

"bell" shape from a cylindrical billet comprising at least three roll-dies suitably journaled, means operating to rotate the roll-dies in synchronism comprising pinions on the roll-dies, a ring gear meshing internally with the pinions and a rack meshing externally with the ring gear, the roll-dies each being formed with portions of reduced diameter adapted jointly to provide a cage space for the reception of a billet introduced axially of the roll-dies, a yieldable stop positioned to be engaged by a billet and comprising a stop element supported by a plunger shaft slidably supported to extend through the ring gear and having a rearward threaded extension, adjusting nuts on the extension to determine the stop forward position and a spring surrounding the plunger shaft and operative normally to retain the stop in forward position and to be yieldable to accommodate for deformation of the billet, and deforming shoulders on the roll-dies extending partially around the circumference and merging with substantially concentric portions effective to roll-finish the deformed billet.

2. A machine adapted for forming a "dumb-bell" shape from a cylindrical billet comprising at least three roll-dies suitably journaled, means operating to rotate the roll-dies in synchronism comprising pinions on the roll-dies, a ring gear meshing internally with the pinions and a rack meshing externally with the ring gear, the roll-dies each being formed with portions of reduced diameter adapted jointly to provide a cage space for the reception of a billet introduced axially of the roll-dies, a yieldable stop positioned to be engaged by a billet and comprising a stop element supported by a plunger shaft slidably supported to extend through the ring gear and having a rearward threaded extension, adjusting nuts on the extension to determine the stop forward position and a spring surrounding the plunger shaft and operative normally to retain the stop in forward position and to be yieldable to accommodate for deformation of the billet, and deforming shoulders on the roll-dies extending partially around the circumference and merging with substantially concentric portions effective to roll-finish the deformed billet, the inner end of each roll-die formed with a cylindrical part with which the adjacent end of the billet makes contact during the reduction of the central or outer part of the billet.

3. A machine for forming a "dumbbell" shape from a cylindrical billet, said machine consisting essentially of a housing having a large opening in the forward portion thereof to form a billet-entry port; at least three substantially parallel and cylindrical roll-dies journaled in the said forward portion of the housing and positioned on the same side thereof and grouped around said billet-entry port in the housing; means operative to rotate the roll-dies in synchronism through 360 degrees; the cylindrical roll-dies each being formed with portions of reduced diameter constituting elongated depressions extending along the roll-dies; said roll-dies so disposed with respect to the housing and to each other, with the portions of reduced diameter facing each other in the idle position of the roll-dies, as to form an open cage for receiving and loosely holding a heated billet entered through the entry port in said housing in the direction axially of the roll-dies with the outer end of the billet floating free; an axially-re-silient stop member supported in the housing and positioned to engage the inner end of the billet to determine the initial axial position of the billet within the said open cage and constructed and arranged to yield upon longitudinal extension of the billet during the rolling operation; a deforming shoulder on the periphery of each of said roll-dies and extending partially around the circumference of the roll-die, said deforming shoulders on the roll-dies so shaped and so arranged with respect to each other that when the roll-dies are turned in the same direction the corresponding portions of the said deforming shoulders will simultaneously engage the billet and roll it to the desired diameter and contour in one revolution of the roll-dies; each of said roll-dies having a re-entrant outer portion at the ends

end of the billet to determine the initial axial position of the billet within the said open cage, adjustable means engaging the stop member to determine the forward position of the stop member, and yieldable means engaging the stop member to bias the stop toward its forward position and yieldable to accommodate the stop to the axial extension-movement of the contiguous end of the billet during the rolling operation; at least a portion of the surface of each of said roll-dies constructed and arranged to form a die-surface extending partially around the circumference of the roll-die, the initial portion of each said die-surface increasing progressively in radius and width and merging with a terminal portion of the die-surface of constant radius effective to roll-finish the deformed billet; said roll-dies so relatively angularly positioned that when the roll-dies are turned in the same direction the corresponding portions of said die-surfaces will simultaneously engage the billet and roll it to the desired diameter and contour in one revolution of the roll-dies; said roll-dies being cut away at their sides adjacent the billet entry port in the housing, said cut-away portions being aligned with said portions of reduced diameter but constituting larger depressions, said cut-away portions and said entry port in the housing cooperating to provide clearance for tongs holding the end of the free-floating billet while said billet is being placed in position to be operated on and while said deformed billet is being withdrawn through the outer end of the said cage, said billet entry port in the housing being devoid of bearing mountings and the like tending to interfere with the free floating and easy insertion of the billet.

4. A machine adapted for forming a part of reduced diameter on a cylindrical billet, said machine consisting essentially of a housing having a large opening in the forward portion thereof to form a billet-entry port; at least three substantially parallel and cylindrical roll-dies journaled in said housing and positioned on the same side of the said forward portion of the housing and grouped around said billet-entry port in the housing; means operative to rotate the roll-dies in synchronism through 360 degrees; the cylindrical roll-dies each being formed with portions of reduced diameter constituting elongated depressions extending along the roll-dies; said roll-dies so disposed with respect to the housing and to each other, with the portions of reduced diameter facing each other in the idle position of the roll-dies, as to form an open cage for receiving and loosely holding a heated billet entered through the entry port in said housing in the direction axially of the roll-dies with the outer end of the billet floating free; an axially-re-silient stop member supported in the housing and positioned to engage the inner end of the billet to determine the initial axial position of the billet within the said open cage and constructed and arranged to yield upon longitudinal extension of the billet during the rolling operation; a deforming shoulder on the periphery of each of said roll-dies and extending partially around the circumference of the roll-die, said deforming shoulders on the roll-dies so shaped and so arranged with respect to each other that when the roll-dies are turned in the same direction the corresponding portions of the said deforming shoulders will simultaneously engage the billet and roll it to the desired diameter and contour in one revolution of the roll-dies; each of said roll-dies having a re-entrant outer portion at the ends

of the roll-dies adjacent the billet entry port, said re-entrant portions being aligned with said depressions in the roll-dies but constituting larger depressions, said re-entrant portions of the roll-dies and said billet entry port in the housing co-
 5 operating to provide clearance for tongs holding the end of the free-floating billet while said billet is being placed in position to be operated on and while the deformed billet is being withdrawn axially through the outer end of said cage, said 10 billet entry port in the housing being devoid of bearing mountings and the like tending to interfere with the free floating and easy insertion of the billet.
